(57) **CLAIM**

The ornamental design for a microscope, as shown and described.

DESCRIPTION

This application contains subject matter related to the following co-pending U.S. design patent application:
Application Ser. No. 29/621,277, filed herewith and entitled “microscope”.

FIG. 1 is a left, front perspective view of a microscope according to the design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate environmental subject matter only and form no part of the claimed design.
